[57] CLAIM

The ornamental design for a combined telephone set and base therefor, as shown.

DESCRIPTION

FIG. 1 is a perspective view of a combined telephone set and base therefor, showing our new design;

FIG. 2 is a side elevation thereof, of an enlarged scale, the opposite side being a mirror image of the side shown;

FIG. 3 is a rear elevation thereof, of an enlarged scale; and

FIG. 4 is a front elevation thereof, of an enlarged scale.

FIG. 1

FIG. 2

FIG. 3

FIG. 4
